PUSH-BUTTON RADIO TUNER

Joseph L. Swallow, Lombard, Ill., assignor to
Wells-Gardner & Co., Chicago, Ill., a corpora-
tion of Illinois

Application February 24, 1940, Serial No. 320,591

29 Claims. (Cl. 250—20)

This invention relates in general to a remote controlled radio tuner operated by push buttons, and is more particularly described as an installation of this kind for automobiles.

An important object of the invention is in the provision of an improved step by step push control together with visual and illuminated means for indicating the different station positions.

A further object of the invention is in the provision of a step by step tuning device which is readily variable and adjustable.

Still a further object of the invention is in the provision of improved manual control means in connection with the push button and tuning devices by which it is possible to select stations other than those included in the step by step station selection.

Further objects of the invention are in improving and simplifying the mechanisms of the push button and tuning portions for economical production, practical assembly and operation, and satisfactory installation, control, repair and replacement.

Other objects of the invention will appear hereinafter, the preferred construction being illustrated in the accompanying drawings illustrating a preferred embodiment of the invention, in which

Fig. 1 is a sectional perspective illustrating the invention as installed in an automobile;

Fig. 2 is a sectional view taken on the line 2—2 of Fig. 1 showing one position of a portion of the step by step and tuning mechanism;

Figs. 3 and 4 illustrate different positions of the mechanism also shown in Fig. 2;

Fig. 5 is an elevation of the outside of the mechanism from the side opposite that shown in Fig. 2;

Fig. 6 is a top or plan view of the mechanism shown in Fig. 1;

Fig. 7 is a sectional view taken on the line 1—1 of Fig. 6;

Fig. 8 is a sectional detail taken on the line 8—8 of Fig. 7;

Fig. 9 is a sectional detail taken on the line 9—9 of Fig. 6;

Fig. 10 is a perspective of the transverse step by step adjustment shaft;

Fig. 11 is an enlarged view of the front of the manual control plate;

Fig. 12 is a rear view of the control plate and parts supported thereby;

Fig. 13 is an enlarged sectional detail of the push button control taken on the line 13—13 of Fig. 11;

Fig. 14 is a detail cross section taken on the line 14—14 of Fig. 13; and

Fig. 15 is an enlarged sectional detail of the manual control mechanism taken on the line 15—15 of Fig. 11.

This invention does not depend for its novelty upon the radio circuits, connections, or devices, except for the connection with the parts necessary to effect a variation of wave lengths or volume in tuning in different stations. The step by step and independent tuning mechanism will first be described and then the connection of the manual push button and independent controls which relate thereto.

Referring now more particularly to the invention, a radio cabinet 20 is shown supported by a front panel 21 of an automobile below the cowl or hood thereof and at the rear of a front instrument panel 22 in which a manual control plate 23 is inserted for convenience in manually operating and observing the radio from the front seat of the vehicle. The radio set receives current from a battery 24 which may be the battery of the automobile or an independent one connected by suitable conductors 25 to the radio receiver itself and also having a ground connection 26 which may be connected to a suitable frame part 27 of the vehicle.

Within the radio cabinet are a number of tuning condensers 28 (Figs. 6 and 7) or other parts for varying wave lengths in tuning in different stations having movable parts connected by thin wires 29 to a common cross head 30 which is movable toward and from the parts 28 to produce the desired wave length variations.

At the ends of the cross head 30 are perforated ears 31 to receive the ends of a mounting cross bar 32, the extremities of which extend through opposite slots 33 in end plates 34 and 35. At the outer side of each end plate 34 is an arm 36 pivoted at its lower end upon a transverse shaft 37 mounted in the end plates and each having a slot 38 at its upper end extending across the slot 33 and engaging the end of the cross shaft 32. The shaft 37 has a projection 39 at its underside engaged by end of a coil spring 40 (see Fig. 7), the other end connected to a supporting plate 41 through which the control wires 29 extend, the action being such that the spring 40 tends to rotate the shaft 37 and the upper ends of the arms 36 to move the cross head 30 and the wires 29 outwardly from the plate 41 and the tuning devices 28. In seating or positioning the cross shaft 37 in the end plates, either one or both of them may be provided with an undercut re-

cess 42 at the lower edge into which the shaft is inserted and held against removal by the spring 40.

A toothed adjustment shaft 43 is rotatably mounted in the end plates between two spacing and supporting plates 44 and the free rotation of this shaft is prevented by a contact spring 45 extending between the upper ends of the plates and engaging in a reduced groove 46 near one end of the shaft. At one end of the shaft outside of the end plate 35 is a step by step control disc 47 having teeth 48 projecting therefrom, and on the shaft itself are helically spaced teeth 49 and a tooth 50 corresponding to the teeth of the disc.

Overlying the adjustment shaft 43 is the step by step and manual tuning mechanism which comprises a number of push button sleeves 51 and a manual control sleeve 52, each formed with a transverse perforated projection 53 at its upper side through which a mounting shaft 54 extends, the ends of the shaft being suitably secured in the end plates 34 and 35 so that each sleeve is free to rotate thereon but is drawn downwardly at its inner end by a coil spring 55 attached at one end to a flange 56 of the supporting plate 41 and having an extension 57 at the other end attached to a hook 58 adjacent the mounting projection 53. The springs 55 tend to depress the inner end of each of the sleeves so that they are pressed downwardly in engagement with the upper end of one of the cross plates 44.

Each sleeve 51 has a threaded perforation 59 at its inner end and a larger opening 60 throughout the remainder of the sleeve for receiving the threaded portion of an adjusting screw 61 in the threaded portion 59 and for loosely receiving a head 62 of the screw in the opening 60 of the sleeve. The outer extremity 63 of each adjustment screw is rounded and unthreaded and is adapted to engage in an angular seat formed at the lower edge the cross plate 30 by a flange 64 extending from the lower edge of the cross plate having an angularly up-turned edge 65 and by securing thereto a plate 66 having an angular downwardly turned edge 67. In a similar manner the sleeve 52 receives a threaded screw 68 having an unthreaded and rounded extremity 69 projecting through the inner end of the sleeve; and surrounding the screw is a hollow shell 70 accommodated in a recess 71, the shell being formed with a longitudinal slot 72 slidably receiving a pin 73 which projects from the adjacent end of the screw. Attached to the outer or free end of the shell 70 is a flexible cable 74 by means of which it may be turned in either direction, the rotary movement of the shell producing a corresponding longitudinal movement of the screw in the threaded end of the sleeve 52.

All of the adjustment screws 61 and 68 are moved by their springs 55 to a position engaging the upper edge of the cross plate 44 where they are out of alignment and below the angular engagement notch of the cross plate 30.

In order to place any one of the adjustment pins into alignment with the angular notch of the cross plate 30 the adjustment shaft 43 is rotated until the proper tooth 49 or 50 is moved by rotation of the shaft to raise it into the desired engaging position. This shaft is moved in a step by step motion and is shown with six teeth corresponding to the six teeth in the ratchet disc 47 and to the five step by step sleeves 51 and one manual adjustment sleeve 52 of the tuning device.

In order to accurately adjust the screws in the sleeves 51 a thin plate or screw driver is inserted in the opening 60 into engagement with the slot in the head 62 of the screw for adjusting it in either direction to vary the tuning for that particular device. Each screw is frictionally held in its sleeve 51 by cutting a notch 75 at one side thereof intersecting the threaded opening 59 (see Fig. 8) and a contact pin 76 is placed around the rest of the sleeve member but disposed in the slot in contact with the exposed threaded edge of the screw; the ends of the pin are looped or twisted together, and thus the screw is held frictionally against loosening movement in either direction.

At the same time the adjustment shaft 43 is rotated in a step by step movement, the tuning cross-plate 30 is also actuated in order to move its angular engagement notch free from contact with any one of the adjustment screws. This is effected as shown more clearly in Figs. 2, 3 and 4 by an escapement mechanism comprising a slide 77 located at the outside of the side plate 35 adjacent the ratchet disc 47 and mounted at the top is a guide rod 78 supported at one end by the plate 41 and at the other end in an ear 78' struck out of the side wall 35. At the bottom the slide is mounted upon a rod 79 secured at one end to the plate 41 and at the other end in a bent extremity 80 of the side plate 35. At its lower end the slide is formed with an upwardly projecting angular extremity 81 bent to engage the ratchet teeth 48 limiting the movement of the ratchet as shown in Fig. 4. This extremity is also engaged and moved by contact with the end of the push button slide bar 82 so that each time the push button is actuated the slide 77 is moved into the path of the ratchet teeth 48 against the tension of a spring 83 connected at one end to a plate extension 84 of the slide and at the other end to a fixed projection of the end plate. This plate projection has an angular tooth 85 at the side of the ratchet 47 opposite the angular end 81 and normally is held in engagement with one of the teeth 48 as shown in Fig. 2, by means of the spring 83.

Mounted in the ends of the slide 77 is a slideable escapement bar 86 having a tooth 87 adapted to engage the teeth 49 of the escapement disc and having a spring 88 connected at one end to the slide bar and at the other end to the escapement bar tending to move it in a direction opposite to the movement of the slide bar by its spring 83, the escapement bar having a projection 86' for limiting its movement in the slide bar and the construction and arrangement being such that when the slide 77 is at rest at one end of its movement as shown in Fig. 2, the escapement tooth 87 is free from engagement with the teeth 48 of the escapement disc which are then held in place by the holding tooth 85 of the slide bar. As soon as the slide bar is moved to the left by the push button bar 82 the escapement tooth 87 engages one of the lower teeth 48 as the tooth 85 is drawn outwardly from engagement with the opposite upper tooth. The continued movement of the slide to the left causes it to engage a projection 89 extending from the cross bar engaging arm 36 thus moving the cross bar 32 and the tuning cross plate to the left and free from a position where it will engage any of the adjustment screws 61 or 68. This continued movement will cause the escapement tooth to move the escapement disc one step or one tooth until the next tooth 49 comes in contact with

the angular extremity 81 of the slide plate. The release of the push button slide bar will cause the spring 83 to return the slide bar 77 from its advanced position, the stop tooth 65 will be moved into engagement with the next escapement tooth, and with further returning movement of the slide 77 the latter will engage the stop 86^a of the escapement slide bar, returning its tooth 87 to a position free from engagement with the escapement teeth as shown in Fig. 2. The return of the slide 77 under the action of its spring 83 will also produce a return of the push button slide bar 82 for its next movement.

Attached to and rotatable with the push button slide bar 82 or with a flexible cable covering 90 thereof is a gear 91 held yieldingly against the bent portion 80 of the end plate 35 by a spring finger 93 which prevents loose movement. This gear meshes with a gear 94 mounted on a shaft 95 and extending to a radio volume control device 96 supported by the end plate 35 and having a number of electric contact terminals 97 for the necessary radio circuit connections. The construction of this particular device is important to the present invention only because of its connection with the push button slide bar 82 which is movable longitudinally to effect the operation of the step by step slide 77 and is rotatable to operate the volume control device.

At the end of the adjustment shaft 43 opposite the ratchet disc 47 is a flat portion 98 adapted to engage in a disc 99 (see Figs. 5 and 6) which is rotatable in a perforation in an insulation disc 100 supported by brackets 101 to the side plate 34. A plurality of separate openings 102 are made in the edge of the opening of the plate 100 below the outer edge of a split contact ring 103 secured to and rotatable with the disc 99, the ring extending beyond the edge of the disc and overlying the edges of openings 102. Opposite each opening 102 at the outer side thereof is a perforation 104 in the insulation plate 100 to provide a simple means for attaching a contact finger and electrical connector 105 by inserting a rivet 106 therethrough and fastening it through the opening 104. Each electrical connector 105 has a finger 107 overlying its opening 102 and inclined upwardly at the edge to receive a contact projection 108 of the contact ring 103 when it is turned by its shaft into engagement therewith. The outer end of each connector has a perforated head 109 for the attachment of a suitable electrical conductor or connection.

Attached to one of the perforations is a connector 110 similar to the connectors 105 but having a spring tongue 111 which extends inwardly to have a continuous connection with the conductor ring 103 at all times except at the split portion of the ring which therefore locates or determines the starting or disconnected position for the radio circuit. When this contact finger 111 is in the split recess of the ring a conductor 112 connected to the electrical contact maker 110 and leading to a lamp at the back of the dial plate 23 will not receive current and the dial will therefore not be illuminated. Electrical current is conducted to the contact ring 103 by one or more electrical connectors 113 having fingers sufficiently long to extend from the under side of disc 100 through an opening 102 and to engage the contact ring at any point of its travel but the contact makers 105 are only engaged in succession as the ring is rotated by the ring projection 108. A number of lamps 114 are

therefore provided corresponding in number to the step by step tooth projections 49 of the adjustment shaft, the arrangement being such that a circuit is closed to one of the lamps corresponding to the projection 49. This tooth also corresponds with the ratchet tooth 48 at the end of the shaft and with the tuning sleeves 51. Thus when the shaft 43 is rotated to any one of its step by step positions a circuit connection is closed at the end of the shaft which lights a lamp for indicating to the operator which tuning device is then in operation.

The sixth tooth 50 and the corresponding position of the operating shaft relates to the manual operating device consisting of the sleeve 52 and the operating screw 68. When the operating shaft is positioned to place the adjusting screw 68 in engagement with the cross head tuning device 30 the cable 74 is manually rotated in either direction and the tuning cross head may be adjusted throughout its entire range of movement without engagement with the step by step operating slide 77 since the projection 89 on the end arm 36 will not engage the slide in its normal or rest position as shown in Fig. 2, but only when the slide has been released and operated by the step by step slide bar 82.

In operating the step by step or manual mechanism there is a step by step knob 115 and a manual knob 116 projecting from the front of the dash plate 23 with a wave length indicator dial 117 conveniently located above and between the two adjustment knobs (see Fig. 11).

In the step by step adjustment mechanism the knob 115 has a transparent dial 118 at its outer end through which an illuminated dial 119 may be observed. The knob 115 and the dial 118 are rotatable together but the illuminated dial 119 is stationary and has numerals 120 or characters designating the different step by step stations. Connected to the knob dial is a shaft 121 which is rotatable and longitudinally movable therewith.

Surrounding the shaft and movable longitudinally therewith is a sleeve 122 held in place 45 on the shaft by spring collars 123 at the ends of the sleeve seated in grooves 124 on the shaft.

This sleeve has radiating projections 125 at one portion of its length forming spaces between them for seating longitudinally extending bars 126 of "Lucite" or similar material which has the property of carrying light throughout its length so that it may be illuminated by lamps as 114, behind the dial plate 23 and transfer the light to the illuminating dial 119 at the front of the knob 115.

In the knob at the end of the sleeve is an outwardly extending projection 127 having perforations 128 through which the lighting bars 126 extend, the forward edge of the projection also being secured to and carrying the numeral dial 119 in position immediately back of the transparent dial 118.

The knob projection 115 is insertable within a cylindrical housing 129 connected firmly at its rear end to the dial plate 23 so that the knob may be depressed therein for a step by step movement of the shaft and of the flexible slide bar 82 and cable 90 attached to the rear end thereof. The sleeve 122 and one or more of the projections 125 thereof are seated in a groove 130 of a supporting shell 131 so that the sleeve 122 is movable longitudinally with the shaft 121 and the knob 115 but does not rotate therewith.

At the outer end of the shell is a flange 132 for engaging a collar 133 which in turn engages the

outer edge of an opening through the dial plate 23 and the outer surface of the shell is threaded for attaching the plate by means of a fastening nut 134 to the inside of the supporting plate. At the extreme inner end of the sleeve is a tubular fitting 135 for extending over the slide bar and cable connection attached to the end of the cable connection 121. In the wall of the shell inside of the supporting plate are a number of openings 136 corresponding to the spaces between the partitions 125 of the sleeve member 122, each communicating with the light transmitting bars 126 therein.

Mounted on the outside of the shell is a lamp assembly comprising a multiple holder 137 having front resilient portions 138 with opposite notched portions 139 for engaging bayonet mounting pins 140 for the small electric lamps 114 corresponding in number with the openings 136 and each lamp having a central insulated lighting contact 141 which presses against the central end contact of the lamp and separate conductors 142 leading thereto and to the corresponding contact makers 105 in the tuning device cabinet 20.

The manual control knob 116 is connected to a shaft 143 which extends through the dial plate 23 and the dash support and at the rear thereof a gear 144 is secured to the shaft which meshes with an idler gear 145 and it in turn meshes with a gear 146 which is connected to an indicator or pointer arm 147 which moves over the dial 111 at the front of the plate 23. The shaft also continues rearwardly and is connected to the cable 14 which extends to the manual control adjusting screw 68 in the tuning cabinet.

By the operation of the manual control knob 116 the radio may therefore be tuned entirely independently of the step by step or push button controls, and when the push button controls are in operation, the movement of the manual knob will cause a rotation of the pointer 147 but will have no effect upon the tuning.

In operating the push button knob 115 the rotation of the knob will serve to connect the radio circuits to the battery or other source of current supply and this may be evidenced by turning on a lamp 148 connected to conductor 112 at the rear of the dial 111 (see Figs. 11 and 12) which will illuminate the dial, or if desired this circuit may be arranged by a proper connection with the contact makers 105, 110 so that this dial will be illuminated only when the manual control is in operation. Whenever the push button selectors are in operation the corresponding dial number 120 will be illuminated to indicate which of the selected stations is at that time in operation.

I claim:

1. In a direct radio control, a single rotatable and repeating depressible station selecting push button, a separate manually rotatable station selecting control knob, a step by step tuning mechanism connected for operation by the push button to select any one of a plurality of stations in succession, means at one step by step position of the push button for connecting the tuning mechanism for operation by the rotation of the control knob to mechanically select any station, and volume control means operated by rotation of the push button.

2. In a direct radio control, a single repeating depressible station selecting push button which is also rotatable, a separate manually rotatable station selecting control knob, a station tuning mechanism having a plurality of predetermined stations connected for successive selection by the re-

peated operation of the push button and a portion of the mechanism being also rotatable for selecting any station, means at one successive position of the push button for connecting the control knob to the rotatable portion of the tuning mechanism for rotatable selection of any station, and rotatable volume control means connected for operation by the rotation of the push button.

3. In a radio control, a single rotatable and depressible repeating station selecting push button, a separate manually rotatable station selecting control knob, a station tuning mechanism having step by step and rotary station selecting means, means connecting the push button for operating the step by step means to select any one of a plurality of stations by successive depressions thereof, means at one position of the push button for disconnecting it from the tuning mechanism and for connecting the control knob thereto for manual rotation of the station selecting tuning means to select any station, and volume control means operated by the rotation of the push button independently of the station selected.

4. In a radio control, a single depressible repeating station selecting push button which is also rotatable, a separate manually rotatable station selecting control knob, a station tuning mechanism having step by step and rotary station selecting means, means connecting the push button for operating the step by step means to select any one of a plurality of stations by successive depressions thereof, means in one position of the push button for disconnecting it from the tuning mechanism and for connecting the control knob thereto for manual rotation of the station selecting tuning means to select any station, an indicator in connection with the knob to show the station for which the tuning mechanism is set by the rotation of the knob, and volume control means connected for operation by the rotation of the push button for either push button or manual knob station selection.

5. In a radio control, a single depressible push button, a rotatable manual control knob normally disconnected for tuning, means in connection with the manual control knob for indicating the position in which it is set, a step by step tuning mechanism connected for operation by the push button and at one step position the tuning mechanism being connected for operation by the manual control knob, and illuminated indicators in connection with the push button to indicate which one of a plurality of predetermined stations has been selected thereby for operation.

6. In a radio control, a depressible push button, a rotatable manual control knob normally disconnected for tuning, an illuminated station indicator operated by the rotation of the control knob, a tuning mechanism operated by the push button to tune in a succession of predetermined stations and then to place the tuning mechanism under the control of the rotatable manual knob for complete tuning movement, and illuminating means in the push button for indicating that one of the stations controlled thereby which has been selected and tuned in by the operation of the push button.

7. In a radio control, a rotatable and manually depressible step by step repeating push button, a step by step tuning mechanism operated to tune in a succession of predetermined stations by successive depressions of the push button, volume controlling means operated by the rotation of the push button, and a non-rotatable illuminated in-

indicator in the push button to show which station is tuned in.

8. In a radio control, a single rotatable and manually depressible step by step repeating push button, a step by step tuning mechanism actuated to tune in successive stations by successive depressions of the push button, a non-rotatable station indicator within the push button and visible at the front thereof, and means for illuminating the station indicator depending upon the position of the step by step mechanism.

9. In a radio control, a depressible push button, a step by step station tuning mechanism actuated by successive depressions of the push button, a station indicator within the push button comprising a dial with station designations thereon, a plurality of lamps corresponding to the stations of the dial, means for concealing the lamps from the front of the dial, and a light transmitting medium extending from each of the lamps to a point adjacent the station indicator in the dial for illuminating the station indicator corresponding to the lamp which is lighted.

10. In a radio control, a depressible push button, a step by step station tuning mechanism operated by movements of the push button, a station indicator carried by the push button and means for illuminating the stations of the indicator in accordance with the tuning mechanism, said means comprising a perforated shell with lights outside of the perforations corresponding to the stations of the tuning mechanism, and a light-transmitting bar extending from each opening to one of the stations of the indicator for illuminating that station indicator only when the corresponding lamp is lit.

11. In a radio control, a rotatable and depressible repeating push button, a station selecting tuning mechanism operated by longitudinal movement of the push button for successively tuning in different stations, other radio control mechanism operated by rotation of the push button, non-rotatable station indicating means carried by the push button and visible at the end thereof comprising a sleeve having radiating projections to form longitudinal passages corresponding to the stations of the indicator, a surrounding shell with openings at a distance from the indicator, lamps opposite the openings, and light-transmitting means in the spaces between the partitions for receiving light from the lamps and transmitting it along the passages to the station indicating means, the station indicating means maintaining the same position independently of the rotation of the push button.

12. In a radio control, a single repeating push button and a shaft connected thereto movable longitudinally and rotatably, station selecting mechanism actuated by longitudinal movement of the shaft and push button, other radio controlling means actuated by rotation of the shaft and push button, station indicating means in connection with the push button comprising a stationary shell in which the shaft is movable having perforations therein at a distance from the push button, a plurality of lamps corresponding to the selected stations arranged opposite the openings, the light therefrom being masked from the front of the push button, means forming separate partitions and passages along the shaft from the openings in the shell to the front of the push button, a visible station indicator surrounding the shaft and supported in the shell against rotation with the shaft at the front of the passages, said means being movable longitudinally

5 with the shaft and push button, and light-transmitting bars located in the passages receiving light through the openings and operative to illuminate the corresponding station indicating means at the front of the push button, the station indicating means being fixed against rotation independently of the rotated position of the push button.

13. In a radio control, a panel mounting plate, a rotatable and depressible repeating push button mounted in the front of the plate, radio tuning means operable to select any one of a plurality of stations by the depression of the push button, other radio control means operated 10 by the rotation of the push button, a non-rotatable station indicator in connection with the push button and visible from the front of the plate, a plurality of lamps at the back of the plate invisible from the front thereof corresponding to the stations controlled by the push button, and light-transmitting means extending from the lamps back of the plate to the station indicating means at the front of the plate for illuminating the station indicating means at the knob 15 corresponding to the stations selected thereby.

14. In a radio control, a movable tuning member, means tending to move the member in a given direction, a plurality of adjustable engaging devices movable into the projected path 20 of the member, and direct mechanical step by step means including a manually depressible push button for moving the devices successively into the path of the member and the number of depressions from the starting position determining the station for which it is tuned.

15. In a direct radio control, a tuning member and means tending to move it in one direction, a plurality of tuning devices pivotally mounted upon a transverse axis, means for moving 25 the tuning devices in succession into the path of the tuning member for setting the tuning member for a predetermined station, and mechanical repeating manual push button means for actuating said moving means in succession for a succession of stations until the desired predetermined station is reached, the number of depressions only of the manual repeating push button from any station position determining the new station which is tuned in.

16. In a direct mechanical radio control, a tuning member and means tending to project it in one direction, a plurality of adjustable tuning devices mounted upon a transverse axis and movable into the projected path of the tuning member, and means for first moving the member 30 free from the tuning devices before it is projected into engagement with any selected one of the devices, said means comprising a step by step mechanism and a repeating manual push button for actuating the mechanism by successive depressions of the push button, different predetermined stations being tuned in by successive depressions only of the push button.

17. In a direct mechanical radio control, a 35 movable tuning member and means for projecting it resiliently in one direction, a plurality of tuning devices movable into the projected path of the member for engaging it at different distances in said path, step by step means for actuating the devices into and out of the paths of the member, escapement means in connection with the step by step mechanism for first moving the tuning member free from any of the engaging devices and then into engagement with

a selected device, and a manual push button for actuating the mechanism by successive depressions thereof.

18. In a direct mechanical radio control, a tuning member including a transverse cross head, means for confining the cross head to a movement in a straight line, spring means in connection with the cross head for projecting it in one direction, a plurality of tuning devices mounted for movement into the path of the cross head, and means for engaging the tuning devices for moving any one of them into the spring projected path of the cross head, said means comprising a step by step mechanism and a push button successively operable to move the tuning devices in succession into the path of the cross head.

19. In a direct mechanical radio control, a movable tuning member, means tending to project the member in one direction, a plurality of tuning devices movable into the path of the member, a shaft with projections thereon for controlling the movement of the devices into the path of the member, an escapement mechanism in connection with the shaft for rotating it with a step by step movement to move the tuning devices into the path of the member, and manual push button means for actuating the mechanism by successive depressions of the push button.

20. In a direct mechanical radio control, a tuning member and spring means tending to move it in one direction, a plurality of tuning devices movable into the path of the tuning member, means for actuating the tuning devices in succession, said means comprising a rotatable shaft with projections thereon for engaging the devices, a toothed escapement member at the end of the shaft, an escapement slide movable to actuate the toothed member in a step by step movement and to engage the tuning member to withdraw it from engagement with one tuning device before the next device is placed in the projected path of the tuning member, and a repeating push button for actuating the escapement slide.

21. In a direct mechanical radio control, a movable tuning member and means tending to project it in one direction, a plurality of adjustable tuning devices separately movable into the projected path of the member, a step by step escapement mechanism for moving the devices in succession into the projected path of the member, a repeating push button for operating the escapement mechanism, and means in connection with one of the devices for manually actuating it to variably engage the member throughout the range of its projected movement independent of the other tuning devices.

22. In a radio control, a movable tuning member and resilient means for projecting it in one direction, a plurality of tuning devices movable into the projected path of the member, a step by step escapement mechanism for determining which of the devices is moved into the path of the member, one of the devices having a manually operable screw for engagement with the member turnable in either direction to move the member against the resilient pressure throughout its entire range of movement independently of the other devices, and a repeating push button for operating the escapement mechanism.

23. In a radio control, a tuning member and means for moving it in one direction, an escape-

ment slide and means for moving it and the member in the other direction, a plurality of tuning devices movable into the projected path of the member for varying the tuning thereof, one of said devices having a manually movable contact for engaging the member to move it throughout its range of movement independently of the other devices, a volume control device and a connection between the volume controlling device and the escapement slide for actuating the device by rotating the means independently of the escapement movement thereof, and a repeating push button for the escapement slide.

24. In a radio control, a tuning member and means tending to project it in one direction, a plurality of tuning devices each movable into the path of the tuning member, one of the devices having an adjustable engaging stop which is manually rotatable for independently moving the member throughout its range of movement, a volume controlling device, a step by step escapement mechanism comprising a shaft with projections thereon for separately engaging the tuning devices and an escapement slide, and a rotatable and longitudinally movable controller including a repeating push button for engaging the slide and the escapement mechanism in its longitudinal movement, and for engaging the volume control device by the rotation thereof.

25. In a radio control, a movable tuning member, a plurality of devices each separately movable into the path of the tuning member, each device comprising a sleeve threaded at one end having a screw threaded in and extending from one end of the sleeve with the head of the screw inside of the sleeve, the end of the screw engaging the member to limit its movement in one direction, and the head of the screw being accessible for adjustment through the opening at the other end of the sleeve, and selective operating means for the devices comprising a step by step escapement mechanism, and a single repeating push button for the mechanism.

26. In a radio control, a tuning member and means for moving it in a predetermined path, a plurality of adjustable devices for engaging and determining the tuning position of the member, each device comprising a movable sleeve, an adjusting screw threaded into and through one end of the sleeve with a slotted head for varying the projection of the other end from the sleeve, a slot in the sleeve intersecting the opening for the screw therein and a frictional contact device around the sleeve and seated in the slot against the threaded screw for holding it therein against turning, and means for operating the devices in succession comprising a single repeating push button.

27. In a radio control, a movable tuning member, a plurality of tuning devices separately movable into the path of the member, a rotatable shaft with projections thereon for determining which device is moved into the path of the member, an escapement mechanism at one end of the shaft for controlling the rotation thereof, a single repeating push button for operating the escapement mechanism step by step and an electrical switch mechanism at the other end of the shaft with indicating means connected thereto for closing circuit connections to the means in accordance with the circuit closing device which is actuated by the shaft, to indicate which tuning device is in operation.

28. In a radio control, a tuning member com-

prising a cross head for connection to a plurality of radio tuning devices, a cross shaft extending through and beyond the cross head, a pair of side plates having straight slots through which the ends of the shaft extend for defining a straight line movement of the shaft and cross head, a pair of arms pivotally mounted upon a parallel axis at a distance from the mounting shaft and having open slots in the ends traversing the slots at the plates, and tuning devices movable into the path of the cross head as determined by the slots in the plates.

29. In a radio control, a tuning member comprising a cross head for connection to radio tuning means and movable in a predetermined path, means in connection with the cross head forming an angular engagement channel, a plurality of tuning devices each comprising a movable contact member for engaging in the angular engagement channel, and means for moving the devices into and out of the path of the cross head and its channel.
